(57) **CLAIM**

The ornamental design for a carry-out box, as shown and described.

DESCRIPTION

FIG. 1 is a front perspective view of a carry-out box, according to the present design in a closed position.

FIG. 2 is a front perspective view of the carry-out box of FIG. 1, in an open position illustrating the interior shelf panel situated horizontally within the carry-out box, according to the present design.

FIG. 3 is another front perspective view of the carry-out box of FIG. 2, in an open position, illustrating the interior shelf panel in an upright position on the carry-out box, according to the present design.

FIG. 4 is a top view of the carry-out box of FIG. 1, according to the present design.

FIG. 5 is a bottom view of the carry-out box of FIG. 1, according to the present design.

FIG. 6 is a front view of the carry-out box of FIG. 1, according to the present design.

FIG. 7 is a left side view of the carry-out box of FIG. 1, according to the present design, a corresponding right side view being a mirror image thereof.

FIG. 8 is a rear view of the carry-out box of FIG. 1, according to the present design.

FIG. 9 is a plan view of the carry-out box of FIG. 1, in a completely unfolded position, according to the present design; and,

FIG. 10 is a sectional view of the carry-out box taken along line 10-10 of FIG. 4, according to the present design.

The evenly-dashed broken lines in all the figures depict perforations and fold lines and form part of the claimed design. Dash dot lines in all the figures depict both boundary lines and parts of the carry out box that form no part of the claim design.
